UNITED STATES PATENT OFFICE

ALBERT LEET GALUSHA, OF CALDWELL, NEW JERSEY

FURNACE

Application filed June 24, 1926. Serial No. 118,243.

My invention relates to furnaces, and particularly to furnaces for domestic heating installations, although its utility is by no means limited to this field. Among the objects of my invention may be particularly mentioned (a) to provide a movable grate furnace, preferably adapted to the combustion of small size coal and having automatically effective means for intermittently moving the grate; (b) an automatic fuel feed and ash discharge incident to the movement of the grate; (c) means for automatically maintaining the fuel bed substantially level and of proper depth for efficient combustion; (d) means for automatically regulating the depth of the ash to maintain the ash bed of appropriate depth, not only to protect the grate and prevent waste of fuel and heat to the ash pit, but also to insure proper draft to the fire; (e) a combined fuel distributor and ash remover which serves also as the conduit for a hot-water supply system for the house; (f) improved grate construction; (g) improved grate operation; (h) improved fuel feed to the grate; (i) improved ash pit and ash removal layout by which labor is saved and dust prevented; (j) correlated means for moving the grate to insure best conditions of the fire for heat production when house temperature is substantially normal; (k) various features of improvements in construction of the furnace parts and in the organization of the furnace as a whole both with respect to structure and operation, as hereinafter described, or as shown in the accompanying drawings, in which

Fig. 1 is a broken side elevation of a furnace in which my invention is embodied in one form certain parts being omitted;

Fig. 2 is a section on the line 2—2, Fig. 1; and

Fig. 3 is a partial vertical section through a grate and fuel bed looking toward the lateral fuel port, the section being that indicated by the line 3—3 in Figures 1 and 2.

The character of the furnace, whether hot air, water, or steam, is immaterial with respect to the features to which my invention relates. For the purpose of explanation I have indicated diagrammatically a boiler furnace 15, the lower portion of which jackets

the fire box 16. The water and steam pipe connections to the boiler and the flues for the products of combustion from the fire box, may be of any appropriate character, and are not shown as they do not enter into my invention. 55

The boiler is supported on the pedestal 17, on the top flange 18 of which rests the outer margin of the rotary grate 19. Fast with the hub 20 of the latter is a vertical shaft 21 which is journalled in upper and lower bearing bosses 22, 23, carried by cross bars or spiders 24, 25 integral with or secured to the pedestal. Preferably the upper bearing boss 22 underlies the hub 20 of the grate, and thus supports the latter in its central area. 65

Fast on the grate shaft 21 is a spider driving wheel 26 of gear, ratchet or other type, the hub 27 of which preferably rests for support on the bearing boss 23. For the sake of illustration I have shown the driving wheel 70 provided with teeth 28 which mesh with the teeth of a pinion or worm 29 on the driven shaft 30. The latter may be driven by any suitable means, for example by an electric motor 31, or, if preferred, by a piston, to the 75 cylinder of which steam is admitted from the boiler 15 through a valve-controlled pipe. Whatever the type of motor, the supply of power thereto is automatically controlled, as hereinafter mentioned. 80

The end of the driven shaft 30 is preferably squared to receive a hand crank (not shown) for manual operation in emergency.

The pedestal is also provided with a draft opening 32, the door, 33 of which is controllable both manually and automatically. For the automatic control I prefer the hinged door construction shown, which may be lifted by a pull wire 34 connected to the core 35 of the solenoid 36, the circuit of which is closed by a thermostat (not shown) at some desired location within the premises served by the heater. 85

Below the pedestal 17, which is supported upon the floor 37 is an ash pit 38 of sufficient size not only to accommodate one or more ash receptacles 39, but also to permit free lateral withdrawal into the space 40 to one side of the area occupied by the furnace. A hook 41 secured to the ceiling beam 42 100

above the space 40 affords means for the detachable support of a hoisting rig of any desired character for lifting the ash receptacles out of the pit area 40.

5 In order to keep the gear 28 clear of ash, a deflector 43 is arranged within the pedestal above the gear ring to guide the ash into the spider area thereof through which it may fall into the ash receptacle in the pit. Where several barrels are used to receive the ash, a spreader 44 may be used to prevent the ash from falling into the central space between the adjacent barrels.

10 The fuel for the fire chamber is contained in a hopper 45 with inclined bottom 46, the angle of which is sufficient to insure the automatic feed of the fuel to the fire box by gravity. At its lower end the hopper opens to a lateral feed port 47 above the grate. 15 The opening of the port may be regulated by a vertically slideable and adjustable feed gate 48. Inasmuch as different sizes of coal require different depths of fuel bed for proper combustion, the regulation of the port opening 47 is of considerable practical importance.

20 Within the fire box I provide a fuel distributor and leveller 49 and an ash remover or plow 50. Preferably these elements are constituted by upper and lower L sections of pipe, the short legs of which are united by coupling 51 toward the center of the fire bed, while their outer ends are connected to the water jacket of the boiler, or, as indicated 25 and preferred, are passed through the latter to an independent boiler (not shown) in the house water-supply system. A central support for the leveller and plow arms 49 and 50 respectively, may be provided by a 30 branch 52 from the plow section 50, the branch being shaped to engage an upstanding extension 53 of the grate shaft 21. The plow branch 52 also serves to throw ash out from the central area of the grate and thus 35 effect a scavenge of the entire area on rotation of the grate.

40 It will be noted that both pipes 49 and 50 are arranged on chords of the circle defined by the rotary grate, and thus lie at an angle 45 to the direction of travel of the coal and ash as the grate revolves. The distributor arm 49 intersects the path of the coal beyond the fuel port. With respect to this direction of travel, the leading end of the fuel distributor arm 49 is peripheral, and its following end central, while the leading end of the ash plow 50 is central and its following end peripheral. The outer end of the leveller 49 is arranged adjacent the side of the feed port 50 47 toward which the fuel is carried by the drag of the rotating grate. In other words, this outer end is beyond the feed port. Consequently, the fuel entering through the feed port and forced by the grate against the distributor, is deflected and caused by the latter

50 to slide inwardly toward the center of the grate.

The action of the distributor arm or leveller 49 in directing the fuel inwardly is due to the fact that it extends, from a point remote from the grate center and beyond the fuel port in the direction of grate rotation, inwardly in a direction that has a substantial component in the direction in which the grate rotates. By this is meant that the arm 70 diverges from a truly radial line inward from its outer end and this divergence is in the direction of grate rotation. The action of the ash plow arm 50 in directing the ash outwardly is due to its opposite arrangement by which it extends, from a point beyond the ash discharge port in the direction of rotation, inwardly in a direction having a substantial component counter to the direction of grate rotation.

75 Similarly, the plow section 50 enters the wall of the fire box beyond the ash port, being at that side of the ash discharge port 54 which is last passed by the grate during its travel. The ash carried around by the grate and brought into engagement thereby with the inclined face of the plow 50 is caused by the latter to slide outward toward the discharge port 54.

80 To increase the effectiveness of the leveller and plow respectively, the faces thereof which engage the fuel and ash respectively, are preferably flat and substantially vertically arranged. For this purpose the pipes may be of rectangular cross section as shown.

85 It will be noted that the plow section 50 is located slightly above the grate surface and thus insures the maintenance of at least a thin layer of ash thereon. This is desirable not only for the protection of the grate 90 against heat injury, but also to secure a more even dissemination of the draft, and to prevent the fall of fresh fuel through the grate. While clinkers and larger masses of ash are sliced off by the plow toward and into the ash discharge port 54, it will be understood 95 that finer ash particles drop through the grate openings at all points, especially when the grate is in motion. It is also pointed out that the lower face of the ash plow is slightly inclined with respect to the grate, its leading edge, the one which first engages the ash, being nearer the grate to prevent grinding of clinkers into the grate holes.

100 I prefer to arrange the fuel feed port 47 and the clinker discharge port 54 substantially opposite each other on the same diameter. When this is the case it will be noted that the fuel distributor 49 lies wholly to one side of the diameter passing through the port centers, while the ash remover or plow 50 crosses that diameter—both locations serving to obtain the slicing action on the fuel and ash respectively, which is desired for the most efficient action of these elements.

I have referred above to the automatic operation of the grate. For this purpose I employ a thermostat 55 located beneath the grate. Inasmuch as this element may be of any suitable character, I have not illustrated it in detail. It suffices to state that at the opposite ends of a predetermined temperature range, the thermostat serves to start or stop the mechanism which rotates the grate.

10 For this purpose when the grate is rotated by means of an electric motor, or electrically controlled mechanism, the thermostat makes or breaks the motor or control circuit 56. Thus, if the temperature beneath the grate falls too low (by reason of too thick an ash bed), the thermostat closes the circuit and the motor revolves the grate with consequent removal of ash by the plow and coincident feed of fuel to the fuel bed. By reason of the ash removal, the hot coals of the fire bed approach the grate and cause a rise in temperature below the latter, which in turn operates the thermostat to open the circuit, thus halting the travel of the grate until the combustion of the fuel and increased depth of the ash bed again reduces the temperature below the grate sufficiently to cause the thermostat to again close the circuit. The rotation of the grate, feed of fuel and removal of ash is thus intermittent, and is automatically controlled by the thermostat incident to varying temperature below the grate.

It will be understood of course that this operation is entirely independent of the house temperature, and that the house thermostat, which I preferably employ for maintaining the house temperature equable, is entirely independent and responds solely to the temperature conditions at the location in which it is placed within the premises. It may be pointed out, however, that when the house thermostat operates by reason of too low house temperature, the consequent opening of the draft door 33 admits air beneath the grate and tends to chill the thermostat 55, with resulting operation of the grate driving motor, the cleaning out of ash, and the refuelling of the grate, so that the condition of the fire for energetic heat production is automatically established when most needed.

In order to start the fire the fire box is provided with a suitable door opening 57, through which kindling, etc., may be laid and ignited on the grate. After the fire is under way, however, the subsequent operation of the furnace is normally fully automatic and may continue for a day, a week or a month, depending upon the size of the fuel hopper and of the ash receptacles.

The operation of the furnace is readily understood from the foregoing. It suffices to point out the intermittent rotation of the grate, governed by the thermostat below the latter, and the automatic feed of fuel and re-

moval of ash to maintain the fire bed in the best condition for combustion of the fuel.

Among the advantages of the construction mentioned may be made of the fact that the hopper may be made large enough to hold a sufficient quantity of fuel to feed the furnace several days or several weeks, as may be; the automatic feed of fuel to, and removal of ash from the grate, obviates the necessity for manual attention for firing; the fuel may be of small size and therefore low priced in the market; the regulation of the depth of the fire bed to suit the type of fuel burned may be accomplished by adjusting the thermostat to various degrees of sensitivity to heat; the fire bed is maintained at substantially constant depth within the predetermined range—and may be quite thin for buckwheat coal, thus obviating the necessity for a blower to obtain the necessary draft, although a blower may be provided and automatically controlled by the house thermostat if desired; the house water supply is heated by the combined fuel leveller and ash remover, and the latter is at the same time water cooled and preserved against heat injury; even soft coal may be used without objectionable smoke or soot; the grate and its accessories may be installed in standard furnaces without difficulty; there is no danger of burning out the grate; the ash pit construction with automatic deposit of ashes in the cans having a capacity sufficient to take care of ashes for a week or several weeks; and the provision of hoisting means for their removal from the pit, simplifies the ash problem; the power required for occasional rotation of the grate is negligible and adds very little to the operating expense. Various other advantages might be specified—many of which are applicable to movable grates of other types than the rotating grate shown by way of example.

It will be understood that the construction illustrated is merely illustrative of the general layout and operation to which my invention relates, and may be modified in many details without departing from what I claim as my invention.

I claim—

1. In a furnace, a rotary grate, lateral fuel feed and ash discharge ports above the grate, and a combined fuel distributor and ash plow having sections at different levels above the grate and respectively associated with said ports to direct fuel inwardly toward and ash outwardly from the central area of the grate during the rotation of the latter.

2. In a furnace, a rotary grate, lateral fuel feed and ash discharge ports above the grate, and a combined fuel distributor and ash plow having sections at different levels above the grate and respectively associated with said ports to direct fuel inwardly toward and ash outwardly from the central area of the grate during the rotation of the latter, said sections

having a flow passage therethrough for liquid.

3. In a furnace, a rotary grate, a vertical shaft below the grate for rotating the same, a spider wheel fast on the shaft for driving the latter, said spider wheel having a peripheral driving rim, driving means for said wheel engaging said rim, and means for directing ash from said rim and through said wheel within its spider area.

10 4. In a furnace, a rotary grate, fuel feed and ash discharge ports, and a stationary pipe extending through the furnace wall and across the firebed, said pipe having a portion extending from a point beyond the fuel port 15 in the direction of grate rotation and spaced above the grate to serve as a fuel distributor, and another portion close to the grate and adjacent the ash discharge port to serve as a plow directing ash to said ash port, and 20 means for connecting said pipe in a liquid flow line.

5. In a furnace, a grate and an ash plow adapted for relative movement, said plow being formed as an arm extending transversely 25 of the grate and having an inclined face presented to said grate, the leading edge of said face being nearer to said grate.

6. In a furnace, a rotary grate, an ash discharge port at the side of said grate, means 30 for directing the ash to said discharge port, a vertical shaft below the grate for rotating the same, a spider wheel fast on the shaft for driving the latter, and means for directing ash from the discharge port and grate 35 through said wheel within its spider area.

7. In a furnace, a rotary grate, a lateral fuel feed port and a stationary fuel distributor arm spaced from the grate and extending across the grate on the far side of 40 said fuel port in the direction of grate rotation from the outside of said grate to a point near the center of said grate and spaced therefrom and so located as to intersect the path of the coal and deflect the coal toward 45 the central part of the fuel bed and level the same.

8. In a furnace, a grate and an ash plow adapted for relative movement, said plow being formed as an arm polygonal in cross section extending transversely of the grate and presenting one face to the grate, said face being inclined to said grate and the edge of said face which first engages the ash being the part of the ash plow nearest the grate.

55 9. In a furnace, a rotary grate, lateral fuel feed and ash discharge ports, an arm extending partially across the grate in a direction having a substantial component in the direction of grate rotation from a point outside 60 of the grate and beyond the fuel port in the direction of grate rotation to deflect fuel toward the central area of the grate and distribute it, a second arm nearer the grate and extending across it from a point below 65 the inner end of said first arm to a point out-

side of the grate and beyond said ash port in the direction of grate rotation to deflect ash toward said ash port and means for supporting said arms at said central area.

In testimony whereof I have signed my 70 name to this specification.
